(57) **CLAIM**

The ornamental design for a electric nasal aspirator, as shown and described.

DESCRIPTION

FIG. 1 is a perspective view of a electric nasal aspirator, showing my new design;
FIG. 2 is another perspective view thereof;
FIG. 3 is a front elevational view thereof;
FIG. 4 is a rear elevational view thereof;
FIG. 5 is a left elevational view thereof;
FIG. 6 is a right side view thereof;
FIG. 7 is a top side view thereof;
FIG. 8 is a bottom plan view thereof; and,
FIG. 9 is an enlarged view of area 9 seen in FIG. 2.
The broken line showing of the electric nasal aspirator is for the purpose of illustrating portions of the article and forms no part of the claimed design. The broken line demarcating the enlarged views forms no part of the claimed design.
